UNITED STATES PATENT OFFICE.

HERBERT A. WAGNER, OF NEW YORK, N. Y.

RAILWAY SIGNALING SYSTEM.

1,264,719.

Specification of Letters Patent. Patented Apr. 30, 1918.

Application filed September 14, 1907. Serial No. 392,836.

To all whom it may concern:

Be it known that I, HERBERT A. WAGNER, a citizen of the United States, residing in the city of New York, in the county and 5 State of New York, have invented certain new and useful Improvements in Railway Signaling Systems, of which the following is a specification.

My invention relates to an electric signaling system for railroads and is especially applicable to railroads operated by electric traction.

My invention is applicable and is especially designed for use in connection with 15 what is known as the block system of railway signaling in which the track is divided into blocks and a semaphore or movable arm or other form of signal at the entrance of each block is automatically operated by 20 the movement of the train past the signal into the block controlled by the signal, the wheels and axles of the train shunting a signal-controlling current in the rails and thereby causing the operation of the signal. 25 My invention is not, however, limited to this specific character of system and in using the term signaling system I desire it to be understood that I intend to include not only a system in which visible signals are operated, but also a system in which any kind of 30 signal or safety device or means for controlling movement of trains is to be automatically operated by the passage of a train along the track.

35 Various features of my invention relate particularly to that general form of railway signaling system which is disclosed and broadly claimed in an application for Letters Patent of the United States filed by one 40 Clyde J. Coleman on July 12, 1907, Serial No. 383,366.

In that form of signaling system the rails of the track are made electrically or conductively continuous and are supplied at intervals with signal-controlling current from suitable sources giving a difference of potential to the rails. The current supplied by each source to the rails is confined to a distinct portion of the track by means of conducting bonds connecting the two rails of the track on either side of the source and forming points of substantially zero difference of potential between the rails. To effect this result the bonds are of negligible 55 impedance, by which I mean that they afford so little obstruction to the passage of

the signal-controlling current that no more than a negligible current could pass from one source of signal-controlling current to the rails beyond the conducting bond on 60 either side of the source.

My invention involves the operation of the signals or safety devices by electro-responsive devices, such as relays for example, each of which receives a current normally 65 determined by some definite proportion of the drop of potential between a source of supply and a conducting bond. The electro-responsive devices are connected to the track in such a way that the difference of potential applied to them when the track is clear 70 will energize them for one operating position, whereas when the track is not clear and the difference of potential between the rails is reduced by reason of the low resistance connection established between them by car wheels and axles, the electro-responsive devices will become sufficiently deenergized to take another position which will cause the signal to assume the danger position. In 75 order to obtain a sharp line of demarcation between blocks so that there will be no undesirable overlap which might cause a signal to go to danger too early or too late, I provide that the normal difference of potential 80 acting upon the electro-responsive devices shall be that which exists between the rails at points in the track a relatively short distance from the nearby conducting bonds, 85 and I prefer to obtain this normal difference 90 of potential by connecting the coil of the electro-responsive device across the track so as to obtain in shunt with the coil the resistance or impedance of both rails from their points of connection with the coil to 95 their points of connection with the conducting bond.

The invention is equally applicable to what is known as the normal danger system, or to a normal clear system. It enables 100 me to dispense with the disadvantages resulting from any attempt to divide the track into insulated sections while using the track for carrying the traction current, and also to avoid any disadvantages due to undesirable overlapping because I provide a sharp line of demarcation between the blocks. These results I attain by an extremely simple system employing only well known and simple forms of apparatus, and 110 without requiring that reliance to be placed upon the use of a number of different

phases or a number of different frequencies of alternating current, or any complexities of this character. Moreover, I am enabled to avoid the use of any inductive bonds, or 5 any use of special kinds of transforming apparatus.

My invention is applicable whether the signal-controlling current be a unidirectional constant current, or an intermittent 10 or alternating current; and my invention is applicable whatever may be the character of current employed for traction purposes.

I will now describe the constructions 15 shown embodying my invention and will thereafter point out my invention in claims.

In the drawings accompanying this specification,

Figure 1 illustrates a system embodying 20 my broad invention in a simple form, the system being shown as a normal clear block system operating home signals only.

Fig. 2 is a diagram illustrating the application of my invention to a normal danger system and showing the operation of both 25 home and distant signals.

Referring first to Fig. 1, A, A' represent the two electrically or conductively continuous rails of a track. The operation of cars on this track is to be under the control of 30 the signaling arms B, B', B² placed at the entrance of the blocks 2, 3 and 4. C, C' and C² are the bonds of negligible impedance which, in the present instance, are placed at the termini of the blocks. By 35 negligible impedance I mean that these bonds should be of such a character as to offer substantially no obstruction to the flow of the signal-controlling current from one rail to the other, thereby establishing a 40 substantially zero difference of potential between the two rails at the points where they are connected to these bonds. If the signal-controlling current be an alternating or other inductive current, the bonds should 45 have a negligible ohmic resistance and also a negligible inductance, while only the former characteristic is essential if the signal-controlling current be a unidirectional or non-inductive current.

Between each pair of bonds the rails are 50 supplied from a source of signal-controlling current. In the present instance I have shown an alternating current generator D which supplies the primaries E, E' of transformers, the secondaries F, F' of which are connected across the rails and preferably about midway in the block or midway between two conducting bonds. When any 55 block is entirely clear of trains a certain 60 definite difference of potential between the rails of the track is established at the center of the block, whereas at each end of the block, because of the conducting bonds, the 65 difference of potential is zero, the current from each transformer F, F' dividing be-

tween two circuits, one through the rails and a conducting bond on one side of the secondary of the transformer, and the other through the rails and the conducting bond at the other side of the secondary.

At any given point between the point of connection of a track-supplying current source or transformer secondary and a bond 70 the difference of potential between the rails will bear a certain value intermediate between zero and the maximum difference of potential given by the source or transformer secondary, but if a car is close enough to the point of connection of a track-supplying source or is between such point of connection and the given point or is beyond the given point but near enough to substantially 75 vary the point of zero difference of potential between the rails of the track, there will be no substantial difference of potential at such given point. Relying upon 80 this principle I supply electro-responsive devices comprising relays governed by coils H to H² which are connected across the rails in order that a definite difference of potential 85 may be applied to them when the track is clear. Relying upon this principle I supply electro-responsive devices comprising relays governed by coils H to H² which are connected across the rails in order that a definite difference of potential 90 may be applied to them when the track is clear. These coils each operate arms h in opposition to a tension device such as the weight h', the relay being so designed that when the normal difference of potential is 95 across the coil the power of the latter overcomes the opposing tension device and closes a local circuit designed to operate the signal and hold it in a clear position as hereinafter described. As indicated, each relay is 100 connected to the rails at a point in the track sufficiently close to a conducting bond so that there will be a sharp line of demarcation between blocks, and yet is sufficiently far from the bond so that there will be a 105 substantial normal difference of potential acting upon the relay.

In the present instance I have shown the signal arms B, B', B² directly controlled by solenoids J, J', J² in local circuits supplied 110 by batteries K, K', K². When any local circuit is closed the signal is held to clear by its solenoid, but the circuit of such solenoid includes in series two of the switches controlled by the coils H to H². The two 115 switches in each local circuit are the switches governed by those coils which are connected to the rails in a block on each side of the point where the signal controlling current is supplied to the rails of that block. Thus 120 the arm B controls block 2. The circuit of the solenoid J for the arm B includes the relays governed by the coils H' H² which are connected respectively at points adjacent to opposite ends of the block 2. In 125 Fig. 1 the block 2 is shown as being free of any car and therefore both relays H' and H² are energized to maintain the integrity of the circuit of the solenoid J, whereby solenoid J receives current from the battery 130

K' and holds the arm B at safety. In block 3, however, I have indicated at L two axles and pairs of wheels of a car or train. These are located between the transformer secondary F' and the points of connection of the coil H³ so that there is substantially zero difference of potential across the terminals of the coil H³, causing this coil to become deenergized, and so opening the circuit between the battery K² and the solenoid J' and setting the arm B' to danger. As the train L moves to the right it will next so nearly short circuit the secondary F' as to cause the coil H⁴ to become deenergized and the circuit to the solenoid J' will therefore be open at two points. A further movement of the train to the right and beyond the secondary F' will finally cause the difference of potential across H³ to rise to a point that will energize that coil and close the local circuit at this point, but owing to the shunting action of the train the local circuit will still be open at the relay governed by coil H⁴ and will remain open at this point maintaining the arm B' at danger until the rear end of the train reaches a point so close to the bond C² as to cause nearly the normal difference of potential to be felt by the coil H⁴. By this time the train will be practically out of the block 3, and the greater part of the train will have passed the bond C² so as to operate the arm B² by the deenergizing of the coil H⁵.

The system therefore meets the usual requirements of a block system, that a signal must always be at danger when there is a train in any part of the block protected by that signal, and in this system the line of demarcation between adjacent blocks is a sharp one inasmuch as the various coils H to H⁵ may be placed near enough to the bonds C to C² to cause no appreciable overlapping.

The system also fulfils the requirement that the signal should go to danger if there is a broken rail, because any break in the rails of the track A, A' between any source and the points of relay connection will cause a cessation of the signal-controlling current and cause the relay in series with the broken rail to become deenergized. Should the rail break between the points of relay connection and the adjacent bond the result would be that the corresponding relay, H or H', etc., would receive a current of much higher potential, substantially the full potential of the source, and I therefore provide fuses s or other overload circuit breakers, in the circuits of such relays, which would break such circuits in the event of a broken rail between the point of relay connection and a connecting bond.

If electric traction is to be used for train propulsion, the rails of the track would naturally be used as return conductors for the traction current. The rails being electri-

cally continuous, would form the best possible electric conductor for traction current, and the heavy cross-bonds of low resistance would facilitate the equalization of this current between the rails, while at the same time the traction currents and signaling currents would in no way interfere with each other. I have shown in Fig. 1 a generator G for traction current, connected to the rails at one of the bonds, and a trolley wire or third rail T, and a current collector or trolley t on the car L, L.

Referring to Fig. 2, I have shown the system applied to the more complex conditions of home and distant signals, and to a normal danger system. So far as applicable the same letters of reference are applied in this figure as in Fig. 1. In Fig. 2 the home and distant signals B and M are both shown at danger, and a train L is shown in the block 2. The home and distant signals B' and M' are both shown as cleared by the approaching train L in block 2, there being no train in block 3 or block 4 to maintain either of these signals at danger.

In Fig. 2 the coils H², H⁴, H⁶ and H⁸ govern movable contact fingers and correspond to the coils H to H⁵ of Fig. 1, while the coils H', H³, H⁵ and H⁷ of Fig. 2 govern similar movable contact fingers which, however, have back contacts k included in the local signal circuit of the block ahead so that the local signal circuit of the block ahead cannot be closed to set its signals at clear except by a train approaching the block while maintaining the signal behind the train at danger. In Fig. 2 the local circuits are shown as supplied by transformers N to N'.

In series with each of the coils J to J³ controlling the home signals are coils O to O³ controlling movable contact fingers, each in series with the corresponding coil, P to P³, controlling a distant signal. Whenever, therefore, a home signal is at danger because of the deenergizing of its coil J or J', etc., the circuit of the corresponding coil P or P', etc., is open, and therefore the distant signal, M or M', etc., must also be at danger.

The home and distant signals B, M, are both at danger, and cannot be cleared because the train L in block 2 is at such a position as to deenergize the coil H³ and thereby open the circuit from the secondary of transformer N' to the coils J and O. This same circuit to the coils J and O is also opened at the back contacts K because it is assumed that there is no train in the block 1.

The signals B' and M' are both cleared because the train L in block 2 has deenergized the coil H³, closing at the back contacts k the circuit of the solenoid J' and coil O'. As there is no train in block 3 the circuit from the transformer N² is completed through the front contacts of the relay H⁴.

and H^5 of block 3, and thence through the back contacts h of the relay H^3 . The current which clears the home signal B' closes the switch controlled by the coil O' and the 5 distant signal M' is put to clear because the circuit of its actuating coil P' is completed by the front contacts of the relays of the next block ahead, block 4. The actuating coil J' of the home signal B' is therefore in 10 the local circuit of the transformer N^2 , while the actuating coil P' of the distant signal M' is in the local circuit of the transformer N^3 . If there were a train in block 4 one of the relays of that block would open its front 15 contacts, wherefore the distant signal M' would be held at danger despite the clearing action of the train L in block 2.

There being no train in block 3, both signals B^2 and M^2 are at danger because the 20 circuit of the actuating coil J^2 is open at the back contacts of the relay H^5 . Inasmuch as there is no train in the block 4, the circuit of the coil J^2 is otherwise complete, and if a train should enter block 3 the home signal 25 B^2 would be cleared. The distant signal M^2 would not be cleared, however, because there is a train in the block 5 and the circuit of the actuating coil P^2 of the distant signal M^2 is therefore opened by the front contacts of 30 the relay H^8 , so that no train in block 3 could clear the distant signal M^2 .

The home and distant signals B^2 and M^2 are at danger and cannot be cleared because of the train L in block 5, the circuits being 35 the same as in the case of the devices controlling signals B and M .

In Fig. 2 I have indicated that step up 40 transformers Q might be used between the coils H^1 to H^8 and the track connections. This may be desirable in order to increase the potential across the coils and permit the use of smaller wires to and in the coil.

It is obvious that various modifications 45 may be made in the constructions and arrangements of circuits shown and above particularly described, all coming, however, within the principle and scope of my invention.

Having thus described my invention, what 50 I claim as new and desire to secure by Letters Patent is:

1. In a railway signaling system, electrically continuous track rails, a conducting bond connecting the opposite rails of the 55 track, a source of electric current arranged to create a difference of electric potential between the rails of the track at a point distant from said bond, and an electro-responsive signal controlling device operatively related to the track rails to receive a substantial-working current determined by the drop of potential of the potential in a definite portion of the track between said bond and said source.

2. In a railway signaling system, electrically continuous track rails, a conducting 60

bond connecting the opposite rails of the track, a source of electric current arranged to create a difference of potential between the rails of the track at a point distant from said bond, and an electro-responsive signal 70 controlling device connected with the track rails at a point intermediate the source and bond so as to receive a substantial working current determined by the drop of potential in a definite portion of the track between 75 said bond and said source.

3. In a railway signaling system, electrically continuous track rails, a bond of negligible impedance connecting the opposite rails of the track, a source of electric current 80 arranged to create a difference of potential between the rails of the track at a point distant from said bond and an electro-responsive signal controlling device operatively related to the track rails to receive a substantial working current determined by the drop of potential in a definite portion of the track 85 between said bond and said source.

4. In a railway signaling system, continuous track rails, a bond of negligible impedance connecting the opposite rails of the track, a source of electric current arranged to create a difference of potential between the opposite rails of the track at a point distant from said bond, and an electro-responsive signal controlling device connected with the rails at a point intermediate the source and bond so as to receive a substantial working current determined by the drop of potential in a definite portion of the track 90 between said bond and said source.

5. In a railway signaling system, electrically continuous track rails, a source of electric current arranged to create a difference of potential between the opposite rails of the track, a bond connecting the opposite rails and determining a point of substantially zero difference of potential between the rails, and an electro-responsive device receiving a substantial working current determined by the drop of potential in a portion of the circuit 105 composed of said source, rails and bond.

6. In a railway signaling system, electrically continuous track rails, a source of electric current arranged to create a difference 110 of potential between the opposite rails of the track, a bond connecting the opposite rails and determining a point of substantially zero difference of potential between the rails, and an electro-responsive device connected to the track rails at points intermediate said source and bond to receive substantial working current determined by the drop of potential 115 in a portion of the circuit composed of said source, rails and bond.

7. In a railway signaling system, track rails, a source of electric current arranged to create a difference of potential between the opposite rails of the track, a bond connecting the opposite rails and determining a 120

125

130

point of substantially zero difference of potential between the rails, and an electro-responsive device connected across the rails at points intermediate said source and bond 5 so as to receive a substantial working current from the rails.

8. In a railway signaling system, a conductively continuous track, a pair of conducting bonds each connecting the opposite 10 rails of the track, an electric source arranged to create a difference of potential between said rails at a point about midway between said bonds, two electro-responsive devices each connected with the rails at the opposite 15 side of the source from the other at points between a bond and the source to receive substantial working currents determined by the drop of potential between said points and bonds, and a signal actuated upon the de- 20 energization of either of said devices.

9. In a railway signaling system, conductively continuous track rails, a pair of conducting bonds each connecting the opposite rails of the track, a source of electric current 25 connected between said opposite rails at a point about midway between said bonds, two electro-responsive devices each connected to the rails at the opposite side of the source from the other at points between a bond and 30 the source to receive substantial working currents determined by the drop of potential between said points and bonds, and a signal actuated by the deenergization of either of said devices.

35 10. In a railway signaling system, a conductively continuous track, a pair of conducting bonds each connecting the opposite rails of the track, an electric source arranged to create a difference of potential between 40 said rails at a point about midway between said bonds, two electro-responsive devices each connected across the rails at the opposite side of the source from the other at points between a bond and the source, and a 45 signal actuated upon the deenergization of either of said devices.

11. In a railway signaling system, a conductively continuous track, a pair of conducting bonds each connecting the opposite 50 rails of the track, an electric source connected between said opposite rails at a point about midway said bonds, two electro-re- 55 sponsive devices each connected across the rails at the opposite side of the source from the other at points between a bond and the source, and a signal actuated upon the de- 60 energization of either of said devices.

12. In a railway signaling system, a conductively continuous track, a pair of con- 65 ducting bonds each connecting the opposite rails of the track, an electric source arranged to create a difference of potential between said opposite rails at a point about midway between said bonds, two electro-responsive 70 devices each connected across the rails at the

opposite side of the source from the other at points between a bond and the source and relatively near to said bonds, and a signal actuated by the deenergization of either of said devices.

13. In a railway signaling system, conductively continuous track rails, a pair of conducting bonds each connecting the opposite rails of the track, an electric source arranged to create a difference of potential between 75 said opposite rails at a point about midway between said bonds, two electro-responsive devices each connected with the rails at the opposite side of the source from the other at points between a bond and the source to 80 receive substantial working currents determined by the drop of potential between said points and bonds, a local circuit controlled by either of said electro-responsive devices, and signaling means controlled by the current in said local circuit. 85

14. In a railway signaling system, conductively continuous track rails, a pair of conducting bonds each connecting the opposite rails of the track, a source of electric current 90 connected between said opposite rails at a point about midway between said bonds, two electro-responsive devices each connected with the rails at the opposite side of the source from the other at points between a bond and the source to receive substantial 95 working currents determined by the drop of potential between said points and bonds, a local circuit controlled by either of said electro-responsive devices, and signaling means controlled by the current in said local circuit. 100

15. In a railway signaling system, a conductively continuous track, a pair of conducting bonds each connecting the opposite rails of the track, an electric source arranged to create difference of potential between said rails at a point about midway between said bonds, two electro-responsive devices each connected across the rails at the opposite side of the source from the other at points between a bond and the source, and signaling means actuated upon the deenergization of either of said devices. 110

16. In a railway signaling system, a conductively continuous track, a pair of conducting bonds each connecting the opposite rails of the track, a source of supply connected between said opposite rails at a point about midway of said bonds, two electro- 115 responsive devices each connected across the rails at the opposite side of the source from the other at points between a bond and the source, a local circuit controlled by either of said electro-responsive devices, and signaling means controlled by the current in said local circuit. 120

17. In a railway signaling system, a conductively continuous track, a pair of conducting bonds each connecting the opposite 125

rails of the track, an electric source arranged to create a difference of potential between said opposite rails at a point about midway of said bonds, two electro-responsive devices each connected across the rails at the opposite side of the source from the other at points between a bond and the source and relatively near to said bonds, a local circuit controlled by either of said 5 electro-responsive devices, and signaling means controlled by the current in said circuit and actuated by the deenergization of either of said devices.

18. In a railway signaling system, conductively continuous track rails, a series of 15 conducting bonds connecting the opposite rails of the track, a series of current supply sources arranged to create a difference of potential between the opposite rails of the 20 track at points between said bonds, a series of electro-responsive signal controlling devices each operatively related to the track rails to receive a substantial working current determined by the drop in potential in 25 a definite portion of the track between a source and an adjacent bond, and signaling means controlled by the signal controlling devices.

19. In a railway signaling system, a 30 source of electric current connected with the opposite track rails which are electrically continuous, a conductive cross-bond connecting the opposite track rails to complete a circuit including the source of current and 35 track rails and bond, an electro-responsive signal-controlling device operatively related to the track rails to receive a substantial working current determined by potential difference established between separate points 40 in the said circuit by flow of current from its said source, and automatic current-limiting means responsive to an excessive potential difference between the said separate points and arranged to limit the current 45 transmitted to the electro-responsive device.

20. In a railway signaling system, a source of electric current connected with the opposite track rails which are electrically continuous, a conductive cross-bond 50 connecting the opposite track rails to complete a circuit including the source of current and track rails and bond, an electro-responsive signal-controlling device operatively related to the track rails to receive 55 a substantial working current determined by potential difference established between separate points in the said circuit by flow of current from its said source, and an overload circuit-breaker arranged to transmit 60 normal currents to the electro-responsive device but operated by an excessive transmission of current to arrest such excessive transmission.

21. In a railway signaling system, electrically continuous track rails, a source of 65

electric current supplying the opposite track rails at a point along the railway, a cross-bond conductively connecting the opposite rails at another point to complete a circuit including the current source and rails and 70 cross-bond, an electro-responsive signal-controlling device operatively related to the track rails to receive a substantial working current determined by potential difference 75 between the opposite rails at a point on the railway between the current source and bond, and automatic current limiting means in control of transmission of current to the electro-responsive device and in turn controllable by the said potential difference 80 determining the current in the electro-responsive device.

22. In a normal danger railway signaling system, a series of signaling blocks of the railway track, in each block a source of 85 signaling current connected to the opposite rails between the ends of the block, in each block two electro-responsive signal-controlling devices deriving signaling current from the rails near the opposite ends of the block 90 respectively, for each block an electrically controllable signal, and for a given block a signal actuating circuit in control of the signal of that block and in turn controllable by both electro-responsive devices of the 95 given block and by one electro-responsive device of the block in rear.

23. In a normal danger railway signaling system, a conductively continuous railway track, cross-bonds conductively connecting 100 the opposite track rails to define successive signaling blocks demarcated by the cross-bonds, for each block a source of signaling current arranged to deliver current to the track rails between the ends of the block and thence in either direction through two oppositely extending rail circuits each including the rails and the bond at one end of the block, for each block two electro-responsive devices having connections respectively with 105 the oppositely extending rail circuits and at points near the ends of the block, for each block an electrically controllable signal, and for each block a signal-actuating circuit in control of the signal for that block and controllable in turn by both electro-responsive devices of that block and also by an electro-responsive device of the block next in rear.

24. In a home-and-distant normal-danger 120 railway block-signaling system, three or more successive blocks of the railway track, suitable means for demarcating the track blocks, for each block a source of signaling current connected with the opposite track rails between the ends of the block, for each block two electro-responsive devices having 125 connections with the block rails near the opposite ends of the block respectively, for a given block a home signal and a distant sig- 130

nal, and suitable intermediary circuits and means whereby the home signal of the given block is governed by both electro-responsive devices of that block and by an electro-responsive device of a block in rear and whereby the distant signal of the given block is governed by both electro-responsive devices of the block next in advance and also by the said three electro-responsive devices which

5 govern the home signal of the given block.

25. In a home-and-distant normal-danger railway block signaling system, three or more successive blocks of the railway track, suitable means for demarcating the track 15 blocks, for each block a source of signaling current connected with the opposite track rails between the ends of the block, for each block two electro-responsive devices having connections with the block rails near the opposite ends of the block respectively, for a given block a home signal and a distant signal, for the given block a signal actuating circuit in control of the home signal of that block and in turn controllable by both electro-responsive devices of that block and also by an electro-responsive device of a block in rear, a relay or circuit-controlling device controlled by the said signal actuating circuit, and another signal actuating circuit 20 in control of the distant signal of the given block and in turn controllable by the relay or circuit-controlling device last mentioned and also by both electro-responsive devices of the block in advance of the given block.

35. 26. In a home-and-distant normal danger railway block-signaling system, a conductively continuous railway track, conductive cross-bonds connecting the opposite track rails at intervals to demarcate successive 40 signaling blocks terminating at the cross-bonds, for each block a source of signaling current connected with the opposite track rails between the ends of the block, for each block two electro-responsive devices having 45 connections with the block rails near the opposite ends of the block respectively, for a given block a home signal and a distant signal, and suitable intermediary circuits and means whereby the home signal of the given block is governed by both electro-responsive devices of that block and by an electro-responsive device of a block in rear and whereby the distant signal of the given block is governed by both electro-responsive 50 devices of the block next in advance and also by the said three electro-responsive devices which govern the home signal of the given block.

27. In a home-and-distant normal danger 60 railway block-signaling system, a conductively continuous railway track, conductive cross-bonds connecting the opposite track rails at intervals to demarcate successive signaling blocks terminating at the cross-bonds, for each block a source of signaling

current connected with the opposite track rails between the ends of the block, for each block two electro-responsive devices having connections with the block rails near the opposite ends of the block respectively, for a given block a home signal and a distant signal, for the given block a signal actuating circuit in control of the home signal of that block and in turn controllable by both electro-responsive devices of that block and also by an electro-responsive device of a block in rear, a relay or circuit-controlling device controlled by the said signal actuating circuit, and another signal actuating circuit in control of the distant signal of the given block and in turn controllable by the relay or circuit-controlling device last mentioned and also by both electro-responsive devices of the block in advance of the given block.

28. In a railway signaling system, the track having conductively continuous rails, sources of electric supply feeding the same at intervals, means for fixing points of substantially zero difference of potential between the rails intermediate successive sources, an electro-responsive device connected across the rails at each side of each of said zero points, so as to receive substantial working current determined by the drop of potential in a definite portion of the track 90 between the adjacent bond and source, and signals in operative relation with said devices.

29. In a railway signaling system, the track having conductively continuous rails, sources of electric supply feeding the same at intervals, means for fixing points of substantially zero difference of potential between the rails intermediate successive sources, an electro-responsive device connected across the rails at each side of and relatively near each of said zero points, and signals in operative relation with said devices.

30. In a railway signaling system, a source of signal controlling current, electrically continuous rails having a closed track circuit supplied by said source, an electro-responsive device in operative relation with said track circuit intermediate its ends, and means for deenergizing said device upon the opening of any part of said track circuit.

31. In a railway signaling system, a series of sources of signal controlling current, a track having conductively continuous rails energized by said sources and means for forming a series of normally closed track circuits fed by such sources said means forming points of substantially zero difference of potential between the rails, and electro-responsive devices connected across the rails at points at each side of and relatively near said zero points.

32. In a railway signaling system, a series

of sources of signal controlling current, a track having conductively continuous rails energized by said sources and means for forming a series of normally closed track circuits fed by such sources said means forming points of substantially zero difference of potential between the rails, transformers each having its primary connected across the rails at one side of and relatively near one 10 of said zero points, and electro-responsive devices each in operative relation with the secondary of one of said transformers.

33. In a railway signaling system, a series of sources of signal controlling current, a track having conductively continuous rails connected at intervals by negligible impedance bonds to form a series of normally closed track circuits fed by such sources, and electro-responsive devices connected across 20 the rails at points at each side of and relatively near said bonds.

34. In a railway signaling system, a series of sources of signal controlling current, a track having conductively continuous rails connected at intervals by negligible impedance bonds to form a series of normally closed track circuits fed by such sources, transformers each having its primary connected across the rails at one side of and 25 relatively near one of said bonds, and electro-responsive devices each in operative relation with the secondary of one of said transformers.

35. In an electric railway system, a series of sources of signal controlling current, a track having conductively continuous rails energized by said sources and means forming a series of normally closed track circuits fed by such sources said means forming 40 points of substantially zero difference of potential between the rails, electro-responsive devices connected across the rails at points at each side of and relatively near said zero points, and a source of traction current having one side connected to said track.

36. In an electric railway system, a series of sources of signal controlling current, a track having conductively continuous rails energized by said sources and means forming 50 a series of normally closed track circuits fed by such sources said means forming points of substantially zero difference of potential between the rails, transformers each having its primary connected across the rails at one side of and relatively near one of 55 said zero points, electro-responsive devices each in operative relation with the secondary of one of said transformers, and a source of traction current having one side connected to said track.

37. In an electric railway system, a series of sources of signal controlling current, a track having conductively continuous rails connected at intervals by negligible impedance bonds to form a series of normally 65

closed track circuits fed by such sources, electro-responsive devices connected across the rails at points at each side of and relatively near said bonds, and a source of traction current having one side connected to 70 said track.

38. In an electric railway system, a series of sources of signal controlling current, a track having conductively continuous rails connected at intervals by negligible impedance bonds to form a series of normally closed track circuits fed by such sources, 75 transformers each having its primary connected across the rails at one side of and relatively near one of said bonds, electro-responsive devices each in operative relation with the secondary of one of said transformers, and a source of traction current having one side connected to said track.

39. In a block signal system, in combination with an electric railway having both rails conductively continuous for all currents, sources of alternating current connected across the rails at intervals, track relays connected in shunt to short lengths 80 of rail, the relays and short rail lengths having such relative impedance as to produce a substantial working current in the relay, and signals controlled by said relays.

40. In a block signal system, in combination with an electric railway having both rails conductively continuous for all currents, sources of alternating current connected across the rails at intervals, signaling devices for controlling the signals connected in shunt to short lengths of rail, 90 the relative impedance of the paths in shunt to each other being such as to enable an effective voltage to be applied to the signaling device, and signals controlled by said 95 signaling devices.

41. In a block signal system, in combination with an electric railway a track composed of two continuous rails, a source of alternating current connected across the 100 rails, a bond of low impedance connected across the rails at a distance from said source, a signaling device for controlling the signal connected in shunt to a short length of rail between the source and the bond, the relative impedance of the paths in shunt to each other being such as to enable an effective voltage to be applied to the signaling device, and a signal controlled 110 by the signaling device.

42. In a block system, in combination with an electric railway a track composed of two continuous rails, sources of alternating current connected across the rails at intervals, bonds of low impedance connected across 115 the rails at points between said sources, signaling devices for controlling the signals connected in shunt to short lengths of rails and adjacent to said bonds, the relative impedance of the paths in shunt to each 120

130

other being such as to enable an effective voltage to be applied to the signaling device, and signals controlled by said signaling devices.

5 43. In a block signal system, in combination with an electric railway having both rails conductively continuous for all currents, sources of alternating current connected across the rails at intervals, signal 10 controlling devices, each having a winding supplied with energy by current shunted around impedance in the track circuit, a substantial portion of said impedance consisting of track rail impedance, the relative 15 impedance of the paths in shunt to each other being such as to direct through said winding a substantial portion of the energy supplied to the winding.

44. In a block signaling system for electric railways, means providing for block signaling while maintaining the opposite traffic rails continuous throughout the blocks and from block to block comprising spaced cross-bonds cross connecting the opposite rails for all currents and demarking the blocks; a translating device; means for impressing a high frequency alternating potential between points on the opposite traffic rails, said points being located intermediate two adjacent cross-bonds; means 20 for utilizing inductive reactance inherent in the steel of the rails of a block for operatively energizing said translating device 25 when the block is clear and being inoperative to cause the operative energization of said translating device when sufficient length of traffic rail in a block is shunted by a train in the block.

the steel of the rails of a block for operatively energizing said translating device when the block is clear and being inoperative to cause the operative energization of 35 said translating device when sufficient length of traffic rail in a block is shunted by a train in the block.

45. In a block signaling system for electric railways, opposite traffic rails continuous from block to block and throughout each block; spaced cross-bonds demarking a block; a translating device; means for impressing a high frequency alternating potential between points on the opposite 40 traffic rails, said points being located intermediate two adjacent cross-bonds; means for utilizing inductive reactance inherent in the steel of the rails of a block for operatively energizing said translating device 45 when the block is clear and being inoperative to cause the operative energization of said translating device when sufficient length of traffic rail in a block is shunted by a train in the block.

In testimony whereof, I have signed my name to this specification, in the presence of two subscribing witnesses.

HERBERT A. WAGNER.
